CLAIM

The ornamental design for see-thru medical manikin, as shown and described.

DESCRIPTION

FIG. 1 is an exploded perspective view of a medical manikin of the present invention, illustrating the manikin and a transparent cover thereof;

FIG. 2 is a front elevational view of the invention, illustrating the transparent cover engaged with the manikin;

FIG. 3 is a right-side elevational view of the invention, illustrating the transparent cover engaged with the manikin;

FIG. 4 is a left-side elevational view of the invention;

FIG. 5 is a rear elevational view of the invention;

FIG. 6 is a top plan view of the invention, illustrating the transparent cover engaged with the manikin; and,

FIG. 7 is a bottom plan view of the invention, illustrating the transparent cover engaged with the manikin.
